G. W. HUMMEL,
FOOT ACTUATED FUEL CONTROL ATTACHMENT FOR MOTOR CARS.
APPLICATION FILED MAR. 29, 1915.

UNITED STATES PATENT OFFICE.

GEORGE W. HUMMEL, OF BEGGS, OKLAHOMA.

FOOT-ACTUATED FUEL-CONTROL ATTACHMENT FOR MOTOR-CARS.

1,208,971.

Specification of Letters Patent. Patented Dec. 19, 1916.

Application filed March 29, 1915. Serial No. 17,918.

To all whom it may concern:

Be it known that I, GEORGE W. HUMMEL, a citizen of the United States, residing at Beggs, in the county of Okmulgee and State 5 of Oklahoma, have invented certain new and useful Improvements in Foot - Actuated Fuel-Control Attachments for Motor-Cars, of which the following is a specification.

This invention relates to motor cars of 10 that type equipped with hand operated mechanism for controlling the throttle valve on the carburetor, and my object is to produce a simple, strong, durable and cheap attachment whereby the throttle valve can be 15 operated by foot power and closed by a spring, the use of such attachment being desirable as it leaves the driver of the car free to retain control of the steering wheel with one hand and operate the brake with the 20 other in the event an emergency stop is necessary.

With the object named in view, the invention consists in certain novel and peculiar features of construction and organization as 25 hereinafter described and pointed out in the appended claim, and in order that it may be fully understood reference is to be had to the accompanying drawings, in which—

Figure 1, is a perspective view of a part 30 of a Ford car equipped with foot attachments for controlling the supply of gas to the engine. Fig. 2, is a vertical section taken through the dash of the car and showing my attachment in side elevation.

35 In the said drawing, 1 indicates the sides of the frame or chassis, 2 the engine or motor, 3 the dash, and 4 the floor of the car adjacent the dash, the floor being omitted from Fig. 1.

40 5 is the stationary support for the steering column 6. The steering wheel is omitted together with its usual equipment for operating the shaft 7 whereby power is transmitted through the crank arm 8 and a link mechanism 45 9 to the operating arm of the usual butterfly valve 10 or its equivalent for controlling the supply of combustible mixture from the carburetor 11 to the engine.

In the Ford car the connection between 50 the arm 8 and the arm of the butterfly valve 10 is a plain rod. To accomplish my object, this rod, in effect has a section cut out of it, and interposed and pivoted to the adjacent ends of the remaining portions is a link 12 55 which link is preferably in the form of a ring, as shown, fulcrumed at 13 on one sec-

tion of the link rod and pivotally connected at 14 to the other section of said rod. I also provide means for operating the link 12 to effect opening or closing of the butterfly 60 valve without affecting the position of the shaft 7 and without interfering with the operation of said shaft to open or close the butterfly valve. The means referred to consists of a spring to hold the link 12 in the 65 position shown by full lines Fig. 1, which represents the closed position of the butterfly valve, and a foot actuated rod for disposing the connected parts in the position indicated by dotted lines, same figure, whereby 70 to open the butterfly valve and supply gas to the engine. The spring is identified by the reference character 15 and the rod by the reference character 16. As shown the rod extends slidingly through the dash and floor 75 4 and is pivotally hooked to an arm 17 of the link ring 12 and the spring 15 is attached at its opposite ends to the pivoted end of said rod and to the dash, this spring when unopposed holding the parts with the gas 80 cut off from the engine. Ordinarily in driving the car, the operator will advance rod 16 by resting one foot against its rear end and when he desires to cut off the supply of gas he removes his foot and permits the spring 85 15 to close the butterfly valve. The rod 16 will have sufficient play in the dash to be capable of swinging laterally when the butterfly valve is operated through rotation of the shaft 7 so as not to interfere with the 90 bodily endwise movement of the link connection constituted by the sections of rod 9 and the link ring 12 connecting said sections.

From the above description it will be apparent that I have produced a foot-actuated 95 fuel-control attachment for motor cars embodying the features of advantage enumerated as desirable and I wish it to be understood that while I have illustrated and described what I now deem the preferred 100 embodiment of the same, I reserve the right to make all changes falling within the spirit and scope of the appended claim.

I claim:

The combination in a motor car, of an engine, a carburetor, a valve for controlling the passage of combustible gas from the carburetor to the engine, a crank arm for said valve, a rock shaft, a crank arm therefor to operate in a vertical plane, a short rod 110 pivoted at one end to the crank arm, a rod aligned with the first named rod and spaced

therefrom and pivotally connected at one end to the crank arm of the valve, a floating lever fulcrumed for movement in a horizontal plane on the first named rod and 5 pivotally connected to the adjacent end of the other rod, a slide rod pivoted at its front end to said floating lever, and a retractile spring attached at its front end to the front

end of said slide rod and at its rear end to a fixed part of the car. 10

In testimony whereof, I affix my signature, in the presence of two witnesses.

GEORGE W. HUMMEL.
